ELECTRIC WAVE FILTER

Edward Cecil Cork, Ealing, London, and Joseph Lade Pawsey, Hillingdon, England, assignors to Electric & Musical Industries Limited, Hayes, Middlesex, England, a company of Great Britain

Application November 9, 1937, Serial No. 173,552
In Great Britain November 18, 1936

7 Claims. (Cl. 178—44)

This invention relates to electric wave filters. It is the chief object of the present invention to provide improved filters which are specially suitable for reducing interference caused by very 5 high frequencies (such as television frequencies) in lower frequency circuits.

For example, it is desirable in direct current leads or in low frequency alternating current leads, to prevent such leads from transmitting interfering signals of the very high frequencies mentioned above. It is also desirable to provide suitably designed filters in interstage couplings, for example, in the grid lead of a thermionic valve, used in amplifiers or modulators, in order 10 to prevent interference by high frequency signals. In addition, in cables employed for connecting a television camera to a transmitter, it is necessary to prevent signals, for example, of the carrier frequency which is usually about 44 15 megacycles, from interfering with the signals transmitting along the cable.

The present invention provides filters suitable for these and other purposes.

According to one feature of the invention, the 25 filter comprises a series reactance of high impedance to a short wave interfering signal and a shunt reactance of low impedance to said signal, at least one of said reactances comprising a shielded inductance self-tuned to the unwanted 30 frequency mainly by virtue of the length of wire employed.

According to another feature of the invention, an electric filter is provided, including a series and a shunt reactance, said series and shunt reactances being mounted within shields connected together in such a manner that the said components and the shields constitute a unitary structure whereby the filter can be readily applied to a lead or cable.

In order that the said invention may be clearly understood and readily carried into effect the same will now be more fully described with reference to the accompanying drawings in which:

Figure 1 illustrates a filter suitable for use in direct current or alternating current supply leads,

Figures 2 and 3 illustrate filters of low capacity and suitable for use in interstage couplings,

Figure 4 illustrates a filter mainly for use in high frequency cables, and

Figure 5 illustrates more in detail the type of filter shown in Fig. 2.

As shown in Figure 1, the filter comprises an inductance 5 and two shunt capacities 6 and 7, the inductance 5 being mounted within a shield

8 which is in the form of a tube the ends of which are closed by insulating members and through which project the ends of the conductor of the inductance 5. In this example and in the following examples the inductances may be wound on insulating bobbins the ends of which fit the internal diameter of the shields. This type of filter is designed for use in the direct current supply leads or alternating current leads of low frequency, such as 50 cycles, for the purpose of preventing interference at high frequencies. The inductance 5 is tuned to the unwanted frequency by virtue of the length of wire employed which is approximately a quarter of the wavelength of the unwanted frequency and thus provides a high series impedance to the unwanted frequency, whilst the condensers 6 and 8 are shunts of low impedance to the interfering signal. In one form of filter designed to prevent interference at 44 megacycles, the inductance 5 10 may be composed of a length of enamelled copper wire (22 S. W. G.) about 5 feet 10 inches long which is thus approximately of a length equal to a quarter of the wave length of the interfering signal and is wound in 51 turns on a former of 15 $\frac{3}{8}$ of an inch diameter, giving an overall length of about $1\frac{1}{16}$ inches; the inductance of the coil so formed is about 4.2 microhenries. The condensers 6 and 8 may each have a capacity of 20 .002 microfarads.

Figure 2 of the drawings illustrates a filter suitable for use as a low capacity filter for an interstage coupling. This filter is a T network and comprises two series inductances 9 and 10 and a series tuned shunt reactance composed of 25 an inductance 11 and a condenser 12. The components shown in Figure 2 are shielded by the provision of shields 13, 14 and 15, these shields being of tubular form and being connected at their inner ends to a hollow junction box 15a. 30 The ends of the tubular shields are connected in any suitable way to the junction box 15a as by screw threading so that the complete assemblage forms a unitary structure. Such a construction is particularly suitable where the filter is designed for use in conjunction with concentric cables composed of an inner conductor air-spaced from a sheath constituting a return conductor. In this case, the shields may have an 35 external diameter corresponding to the internal diameter of the sheath so that the filters can be readily connected to the cable in a telescopic manner. The shield 15 will, of course, in most cases be connected to earth. The inductances 9 and 10, in one example, are tuned by virtue 40 45 50 55 60 65 70 75 80 85 90 95 100 105 110 115 120 125 130 135 140 145 150 155 160 165 170 175 180 185 190 195 200 205 210 215 220 of the length of wire employed and the self-capacities and that due to the screens to resonate at 44 megacycles, the series tuned shunt circuit being arranged to provide a by-pass to earth at the above mentioned frequency. The condenser 12 may have a capacity of 6 micro-micro-farads, whilst the inductance 11 and 44 megacycles is arranged to have an inductance of 2 microhenries. The filter shown in Figure 2 is especially suitable for use in conjunction with a high termination impedance, such as the input impedance of the grid of a valve.

Several filters similar to that shown in Fig. 2 and in the subsequent figures can be connected in cascade.

The filter shown in Figure 3 is similar to the filter shown in Figure 2, with the exception that it is arranged to have less series inductance at television picture frequencies. In this case, two smaller series inductances 16 and 17 are employed associated with a series tuned shunt path similar to that shown in Fig. 2, but associated with each inductance 16 and 17 is a further inductance 18 and 19 each of which may be connected at one of its ends to one of the ends of the inductances 16 and 17 as shown. The inductances 18 and 19 are tuned by virtue of the length of wire employed to resonate at the undesired frequency, which, in one example, may be 44 megacycles. The coupling between the pairs of inductances 16 and 18 and 17 and 19 are such that at television modulation frequencies the series inductance is less than in the case of Figure 2, whereas at the interfering frequency the required high impedance to prevent transmission of such frequencies is present.

Figure 4 shows a somewhat similar type of filter of the unitary construction shown in Figures 2 and 3, but in this case, the filter is designed particularly for use in conjunction with a cable connecting a television camera to a transmitter. In this case the two series inductances 20 and 21 are associated with a shunt condenser 22. The three components are shielded, as previously described and the inductances 20 and 21 are tuned to the unwanted frequency by their self-capacities and the shunt capacities of the shields and virtue of the length of wire employed, which will be approximately of a length equal to a quarter of the wavelength of the unwanted frequency which, in a particular instance, is 44 megacycles. The value of the condenser 22 may be .0002 microfarad and with such an arrangement the filter will function as a low-pass filter having very high attenuation at 44 megacycles, the theoretical cut-off frequency being of the order of 10 megacycles. The filter shown in Figure 4 may be employed for terminating the television camera cable and will be used in series with the line. At modulation frequencies the filter will act as a slight extension of a low attenuation line of the same characteristic impedance, whilst at 44 megacycles which is the frequency of interfering signals, the filter will produce heavy attenuation.

It will be observed from Figs. 1-4 that the shields surround their associated components very closely and thus serve substantially to eliminate direct capacity between the individual reactances. It is found that the use of shields closely surrounding the components is far more effective in reducing direct capacity between the components than the use of a screening box of the usual rectangular form which houses all the components.

Figure 5 illustrates more in detail the mechani-

cal construction of a filter similar to that shown in Figure 2 and also shows the filter connected to a cable and constructed for connection to the main screen of an amplifier or similar device. The parts in Figure 5 corresponding to the equivalent parts in Figure 2 bear the same reference letters and, as shown, the series inductances 9 and 10 and the shunt inductance 11 are wound on bobbins 23, 24 and 25 which fit the internal diameter of the shields 13, 14, and 15, these shields being screw-threaded into the common junction box 15a which is of cubic form. The leads from the adjacent ends of inductances 9, 10 and 11 are connected together in the interior of the box 15a and in order to afford the required connection both in the interior and the box 15a and at the opposite ends of the inductances 9 and 10 the bobbins 25 are provided with rigid conducting rods projecting therefrom the wire of the inductances being passed through holes in the bobbins and wound around the rigid conductors and soldered thereto. The rigid rods which project in the interior of the box 15 after the bobbins are assembled as shown substantially abut against one another and are then soldered together. To enable this soldering to be effected the top of the box 15a is provided with a removable cap 26 permitting access to the interior of the box 15a. The condenser 12 is conveniently constituted by providing on the lower end of the bobbin 25 as shown a conducting disc 27 to which the lower end of the inductance 11 is connected the other plate of the condenser being constituted by a disc 28 having a depression 29 therein, the discs 27 and 28 being separated by a disc of mica 30 constituting the dielectric of the condenser. The provision of the depression 29 permits of adjustment of the capacity of the condenser and for adjusting purposes the two plates of the condenser are urged together by a screw 31 threaded into the interior of the shield 15, the lower end of the shield being closed by a further screw or cap 32.

In the embodiment shown in Figure 5, in order to connect the filter to a cable and to the main screen of an amplifier or similar device, there is provided at the end of the screen 13 remote from the end secured to the box 15a a flange 33 between which and a further flange 34 is clamped a plate 35 which is adapted to be secured to the main screen 36 of the amplifier or similar device. Associated with the flange 34 is a cap 37, the cap 37 and the flange 34 having formed therein a channel 38 in which the sheath 39 of a cable can be clamped, the centre conductor 40 of the cable being connected to the end of the inductance 9. When securing the cable to the filter the cap 37 is removed so that the centre conductor can be soldered or otherwise connected to the rigid conductor projecting from the bobbin 23 and thereafter the cap 37 is secured in position by screws (not shown) and thereby clamping the sheath of the cable between the cap 37 and the flange 34. A similar arrangement may be employed where the filter is used as an interstage coupling in an amplifier.

Where the filter is employed to connect a television cable to an amplifier the shield 13, for example, is arranged to fit into the interior of the lead sheath of the cable the inductance 9 being connected to the centre conductor of the cable. The shield 14 may, in this case be arranged to be received in a suitable socket in electrical contact with the main screening casing of for example an amplifier the input and output leads of 75

the filter being thus disposed on opposite sides of the main screening casing of the amplifier.

We claim:

1. An electric wave filter comprising a series reactance of high impedance to a short wave interfering signal and a shunt reactance of low impedance to said signal, shields for both of said reactances, one of said reactances being an inductance self-tuned to the unwanted frequency mainly by virtue of the length of wire employed.

5 2. An electric wave filter according to claim 1, wherein the filter comprises a T-network the series and shunt reactances being mounted within shields connected together by a common junction box.

10 3. An electric wave filter comprising at least a series and a shunt reactance, and individual shields for both of said reactances, said series reactance comprising a first inductance and a second inductance coupled thereto to reduce the series inductance at a predetermined frequency.

20 4. An electric wave filter according to claim 1, wherein the shields are of circular cross-section.

5. An electric wave filter according to claim 1,

wherein the series reactances comprise inductances self-tuned to the unwanted frequency mainly by virtue of the length of wire employed.

6. An electric wave filter including an inductance and capacity, a bobbin on which said inductance is wound, a conducting element provided at one end of said bobbin and in electrical contact with said inductance, a further conducting element separated from said first element by a member of dielectric material, a depression in one of said conducting elements, a shield surrounding said bobbin and means screw threaded in said shield for adjusting the capacity formed between said conducting elements.

15 7. An electrical wave filter according to claim 1, wherein one of said shields is provided with a flange at one end associated with a junction box so constructed as to enable a cable to be connected to the filter the said flange and junction box enabling the filter to be connected to a conducting screen such as a screening division or box of an amplifier.
